UNITED STATES PATENT OFFICE

2,605,803

PROTECTIVE WRAPPER FOR FRAGILE WARE

Katherine Fletchner, Naperville, Ill.

Application February 3, 1948, Serial No. 5,940

1 Claim. (Cl. 150—52)

1

The invention relates to protective wrappers for fragile ware and more particularly to an improved protective wrapper for storing dishes in the home.

One object of the invention is to provide a protective wrapper of simple, practical construction and attractive appearance for the temporary storage of dishes such as those comprising a dinner service or other fragile china or glassware pieces, in which the individual dishes are effectually protected from contact with each other or with objects which might cause breakage or chipping and in which the dishes are at all times kept in a clean and sanitary condition ready for instant use.

Another object is to provide a protective wrapper capable of accommodating a plurality of dishes or the like in which the dishes are compactly arranged so as to occupy a minimum of space, yet are adequately protected against chipping or breakage.

Still another object is to provide a protective wrapper for dishes which, although constructed of soft fabric, assumes when filled a generally rectangular form permitting a plurality of the filled wrappers to be safely stacked in piles.

A further object is to provide an attractive wrapper for dishes including a cover or outer casing of relatively heavy durable fabric and an inner separating means of soft flexible material adapted to be wrapped around the individual dishes stored therein and to be interposed between adjacent dishes, which is constructed and arranged in a novel manner to facilitate laundering.

Other objects and advantages of the invention will become apparent from the following detailed description of the preferred embodiment illustrated in the accompanying drawings, in which:

Figure 1 is a perspective view of a protective wrapper for dishes embodying the features of the invention, the wrapper being shown in open condition.

Fig. 2 is a perspective view showing the protective wrapper closed.

Fig. 3 is a side elevational view showing the manner in which a plurality of the filled wrappers may be stacked in a vertical pile.

Fig. 4 is a longitudinal sectional view of the wrapper equipped with separating means particularly suitable for the accommodation of flat plates or similar ware.

Fig. 5 is a top view of a protective wrapper showing the manner in which cup-shaped dishes are nested for storage therein.

2

Fig. 6 is a perspective view of the separating means provided in protective wrappers intended for storing cup-shaped dishes.

Fig. 7 is a view of the separating means shown in Fig. 6 illustrating the manner in which the cups are placed in the individual separator pockets.

Fig. 8 is a view similar to Fig. 7, showing the manner in which the pocket material is wrapped around and tucked into a cup.

While the invention is susceptible of various modifications and alternative constructions, I have shown in the drawings and will herein describe in detail the preferred embodiment, but it is to be understood that I do not thereby intend to limit the invention to the specific form disclosed, but intend to cover all modifications and alternative constructions falling within the spirit and scope of the invention as expressed in the appended claim.

The improved protective wrapper for dishes and the like comprises generally a rectangular outer cover or casing 10, which may be made of relatively heavy durable cloth or other suitable fabric, and inner separating means 11 of soft flexible material, such as flannelette, adapted to be wrapped around the individual dishes and to be interposed between adjacent dishes stored in the wrapper. While the wrappers may be used for the storage of any type of fragile ware, for purposes of illustration I have shown the form especially suitable for storing the dishes of a conventional dinner service. In general it has been found desirable to provide a separate wrapper for each type of dish, although in some instances certain dishes commonly used together, such as cups and saucers, may be enclosed in the same wrapper. Thus, one wrapper is provided for dinner plates, another for bowls, another for cups, etc. As such dishes vary in size, the dimensions of the casing 10 may be varied accordingly so that the dishes they are intended to accommodate will fit snugly therein. Likewise, the dimensions of the separating means 11, as well as the form of that means, may be varied to provide the maximum protection for the particular dishes with which they are to be used.

Referring now to Figs. 1, 2 and 4 of the drawings, the outer covering or casing 10 is in the form of a generally flat rectangular bag having top and bottom walls 15 and 16, side walls 17, and an end wall 18. The end of the casing opposite the wall 18 is left open for the insertion and removal of dishes and is provided with suitable closure means whereby the casing may be

tightly closed. To impart stiffness to the casing, the meeting edges of the walls 15-18 are provided with reinforcements which may be in the form of raised seems or bias strips 20.

The closure for the casing 10 is provided, in the present instance, by extending the top and bottom walls 15 and 16 to form flaps 21 and 22 adapted to be folded over the open end of the casing, as shown in Fig. 2. The side walls 17 are also extended to form narrow flaps 23 which can be tucked in under the flaps 21 and 22 when the casing is closed. The flaps may be secured in closed position in any preferred manner, as by tapes or by snap fasteners, as shown in the exemplary container. When snap fasteners are employed, one member 24 of a fastener is applied to the outer flap 21 adjacent its free edge and the other member 25 of the fastener is applied to the lower flap 22 adjacent its inner edge. Preferably, the bias strip 20 is extended around the entire edge of the flap 21 to give the casing a finished appearance and to impart additional stiffness to it when closed.

While the casings 10 are alike in construction, the separating means 11 may vary in form according to the particular type of dish to be accommodated in the wrapper. For dinner or salad plates, saucers, or other flat dishes, separating means of the character shown in Fig. 4 is provided. The separating means in this instance comprises a plurality of rectangular panels 26 of soft, flexible material, such as flannelette secured together as a unit. Preferably, I provide one more panel than the number of dishes to be accommodated in the wrapper so that each dish is interposed between two of the panels and thus effectually protected from contact with adjacent dishes. Moreover, the panels are made wider and longer than the diameter of the dishes, leaving a marginal portion of substantial width at opposite side edges and at the front edge which can be tucked under or wrapped around the edge of the adjacent dish to protect the same.

To facilitate laundering of the wrappers, the panels 26 are secured together by sewing them directly to the casing 10 in a manner which permits the casing to be turned inside out to expose the entire group of panels for washing and ironing. In the exemplary wrapper, each of the panels 26 is secured to the casing at one edge only, preferably the inner or rear edge, which may be sewed to the end wall 18 of the casing by a single row of stitching 27. It will be observed by reference to Fig. 4 that the panels 26 are stitched to the end wall 18 of the casing individually and at vertically spaced points. The particular spacing shown is that provided for flat shallow dishes such as plates. For deeper dishes such as bowls the spacing may be increased as required. This individual attachment of the panels to the casing facilitates the wrapping of the individual dishes and additionally prevents undesirable bunching or distortion of the casing when filled.

It will be appreciated that the flexibility of the panels 26 permits the dishes to be packed in closely fitting or nested relation without danger of chipping or scratching through contact with each other. Moreover, space requirements are minimized and I have found that in the case of flat dishes such as plates, saucers, etc., the wrappers may be conveniently arranged for accommodating as many as a dozen of such dishes. In the case of platters, bowls and other relatively large dishes, it is preferred to construct

5 the wrappers for the accommodation of a smaller number of pieces, as, for example, the number conventionally included in a standard dinner service.

For storing teacups, bouillon cups and similar relatively small cup-shaped dishes, the outer cover or casing 10 is constructed as above described, while the separating means 11 is preferably formed as shown in Figs. 6-8. More particularly, the separating means comprises an elongated base strip 30 of soft, flexible material to which are secured at longitudinally spaced intervals a series of individual dish wrapping elements 31 of the same material as said strip. The base strip may be secured at one end to the casing 10, or, if desired, it may be left free.

While the individual wrapping elements 31 may be of any preferred construction, they are shown herein as rectangular, bag-like receptacles or pockets open at one end. Each pocket is secured to the strip 30 adjacent its open end by a row of stitching 32 extending transversely across the strip and of sufficient length to hold the mouth of the pocket partially open, as illustrated in Fig. 6. The pockets are dimensioned 25 to receive a single cup or the like, such as the teacup 33 shown in Fig. 7, leaving a marginal edge portion of substantial width for tucking into the cup, as shown in Fig. 8.

30 To afford maximum protection, the cups 33 are placed in the pockets 31 with the handles in the lower inside corner so that the group of cups may be nested together, each with its handle disposed within the adjacent cup, as shown in Fig. 5. The wrappers may be conveniently dimensioned to accommodate six cups which when nested together in the manner described above, 35 form a firm compact unit. Each cup is separated from its neighbor by at least two thicknesses of the separating material and its outer surface is protected by the material forming the pocket and by that of the strip 30 which is wrapped around the outside of the assembled cups.

35 To accommodate cups and saucers in the same wrapper, the casing 10 is provided with separating means of both types above described. Thus panels 26 are provided for the accommodation of a plurality of saucers, as, for example, a half dozen, and a pocket type wrapping strip 30-31 is provided for the cups. These are preferably arranged so that the saucers are at the bottom of the casing and the nested cups may rest thereon.

50 By reason of the stiffness imparted by the bias strips 20, the casing 10 when filled with cups nested together as above described, presents a generally rectangular contour that permits stacking with other filled wrappers, as shown in Fig. 3. In stacking a group of filled wrappers, those containing the flat dishes, such as plates, are preferably placed at the bottom of the pile to provide a stable foundation for the same. As each of the filled wrappers is generally rectangular, the piles may be made of substantial height without danger of tipping, thus conserving storage space without endangering the stored dishes.

55 It will be apparent from the foregoing that the invention provides a protective wrapper of simple construction and attractive appearance in which dishes or other fragile ware may be conveniently and safely stored when not in use. The dishes so stored are effectively protected 70 from contact with each other or with objects which might cause chipping or breakage, and

they are kept in a clean and sanitary condition ready for use at all times. Moreover, the filled wrappers may be safely stacked in piles, thus reducing space requirements to a minimum. The improved protective wrapper for dishes is simple in construction and the novel manner in which the separating means is associated with the outer cover or casing greatly facilitates laundering and enables the wrapper to be kept clean and sanitary with a minimum of effort.

I claim as my invention:

A protective wrapper for cup-shaped dishes comprising, in combination, a fabric structure having top, bottom and side walls and one end wall joined together to define a generally rectangular casing, said side walls being extended at the ends remote from said end wall to form flaps adapted to be folded over the open end of the casing, said top and bottom walls also being extended at the ends remote from said end wall to form flaps adapted to be folded over said side wall flaps and one upon the other to form with the first mentioned flaps a dust tight closure for the casing, dish separating means for protecting the dishes stored in said casing including a series of bag-like receptacles each open at one end to receive a single cup-shaped dish and having an extended marginal edge portion for

tucking into the dish, and an elongated base strip of flexible material of a length sufficient to extend around a group of dishes enclosed in said receptacles and assembled in nested relation, said receptacles being secured adjacent their open ends to said base strip and being spaced apart therealong so as to permit the dishes in the receptacles to be nested together in a compact unit and said strip to be wrapped around the outside of said unit.

KATHERINE FLETCHNER.
